US00D560122S

(12) **United States Design Patent** (10) **Patent No.:** **US D560,122 S**
Fuchs et al. (45) **Date of Patent:** **** Jan. 22, 2008**

(54) **POUCH FOR LIQUIDS**

(75) Inventors: **Stephen N. Fuchs**, Corcoran, MN (US); **Martin J. Vievering**, St. Paul, MN (US); **Mark R. Jensen**, Gresham, OR (US); **James M. Delany**, Woodville, WI (US)

(73) Assignee: **Kapak Corporation**, Minneapolis, MN (US)

FIG. 1 is a perspective view of a pouch for liquids showing our new design;

FIG. 2 is a front elevational view of the pouch depicted in FIG. 1, the rear elevational view being a mirror image thereof;

FIG. 3 is a right side elevational view of the pouch depicted in FIG. 1, the left side elevational view being a mirror image thereof;

FIG. 4 is a top plan view of the pouch depicted in FIG. 1; and,

FIG. 5 is a bottom plan view of the pouch depicted in FIG. 1.
